UNITED STATES PATENT OFFICE

2,488,121

FOLDING BOX

Herman L. Greve, Hollis, N. Y.

Application October 1, 1946, Serial No. 700,421

2 Claims. (Cl. 229—14)

1

This invention relates to improvements in folding or set-up boxes, and more particularly to such boxes as may be used to replace the more expensive wood board boxes, such as, for example, those used in packing cigars. Such merchandise as cigars, candy, etc., have to be packed in a container which will preserve the original moisture in the merchandise as long as possible, at least during shipping and storage periods. Boxes of such type also are at present fully assembled when shipped by the box manufacturers and therefore are bulky in shipping and storing before use.

It is an object of the present invention to provide a folding box of unique construction which may be easily set up for containing moisture-retaining articles, and which is particularly adapted for use as a cigar box as it acts as a humidor.

It is another object of this invention to provide a moisture-retainer box which can be shipped and stored in a flat condition, thus taking up a minimum amount of space.

It is a further object of this invention to provide a box of the class described which is preferably made of pulp board, preferably has an external surface or covering simulating wood and which is provided on the inside with a moisture-retainer liner, preferably metal foil.

It is a still further object of this invention to provide means, whereby the box can be set up and filled at the same time.

It is a still further object of this invention to provide a frame for loading the box after the same has been set up and during the filling of the said box, the frame permitting adhesion of the end flaps or walls during the filling period.

It is another object of this invention to cut and score the blank, and arrange the various flaps in a manner which will give the box an aesthetic appearance.

Other objects and the nature and advantages of the invention are fully described in the ensuing specification and the novel features are defined in the appended claims. But this disclosure is illustrative only, and in practice changes may be made in size, shape and arrangement of parts without altering the essential construction of my improved box.

In the drawings:

Fig. 1 is a plan view of a blank of a box embodying the invention.

Fig. 2 shows a sectional view through a partly set up box made in accordance with the invention.

2

Fig. 3 shows a further step in setting up the box.

Fig. 4 shows a sectional view of the complete set-up and closed box.

Fig. 5 is a sectional view taken on lines 5—5 of Fig. 4.

Fig. 6 is a detail sectional view taken on line 6—6 of Fig. 5.

Fig. 7 is a sectional detail view of a frame employed to maintain the sections of the box together while being packed.

Fig. 8 is a sectional detail view of the frame enclosing the partly filled box.

Fig. 9 is a sectional detail view of the packing frame enclosing the loaded and closed box.

Referring now more particularly to the drawings, the blank 10 consists of the bottom portion 11, the cover portion 12, the side walls 13 and 13a and the end walls 14. Walls 11—14 inclusive are lined on the inside with moisture-retaining material such as, metal foil 15. An adhesive 20 is applied to flaps 16, 17, 18 and 19. The height A of the flaps 16 and 18 is slightly greater than the height B of end walls 14 and the flaps 17 and 19. The difference in height is equal to the thickness of the cover 12. The side wall 13 is less in height than the side wall 13a, thus forming the recess 21, which is also equal to the thickness of the cover 12. Thus, when the

box is set up and closed as shown in Fig. 4, the cover 12 will be flush with the outside of the box, the cover resting on edge 22 and shelves 23 formed by the respective adjacently arranged flaps 14, 17 and 14, 19 as seen in Fig. 3. Portions of the blank 10, which form the inside of the completely set up box are lined with metal foil 15 or any other suitable material. While the outer side of the box, is preferably provided with a face 24, simulating wood grain. In assembling the box, the side walls 13 and 13a are folded upwardly on score lines 25 and 26, the end walls 14 are folded upwardly on score lines 27 and 28; while the cover 12 is folded on the score line 29 which separates the cover 12 from the side wall 13a.

Flaps 17 and 19 are now folded on score lines 29 and 30, and after the adhesive 20 has been applied, these flaps are respectively secured to the outside of the end walls 14. The flaps 16 and 18 are also coated with adhesive 20 and are folded on score lines 31 and 32 and adhesively secured to the outside of the flaps 17 and 19. The edges 33 and 34 will thus face rearwardly from the front of the box, adding to the appearance of the box. As soon as the box has thus been set up, the

same is placed in a frame 40, which grips the

box 41 tightly and facilitates the adhesive union of the various wall sections. At the same time, it permits the box to be loaded or filled thus saving time and additional handling. The frame 40 has its upper edge 42 preferably flared as at 43 to facilitate the insertion of the box 41. The opening 44 at the bottom of the frame 40 permits removal of the box from the frame 40, when filled. The straight portion 45 of the frame 40 is preferably less in height than the box 41 to facilitate withdrawal of the filled box from its frame. It is understood, that the cover 12 can be sealed by various means, such as a label 46, or by a latch, not shown, after the box has been filled with the desired articles.

Although it is preferred that the end wall sections 14 and sidewalls 13, 13a be lower than the end wall flaps 16 and 18 to accommodate the edges of the cover and provide seats for the latter, it is to be understood that it is not intended that the invention herein be limited to such construction.

From the foregoing description taken in connection with the accompanying drawing, it is apparent that an improved simple, practical and inexpensive folding-box for the purpose intended is provided. It is apparent however, that immaterial changes and modifications may be made by skilled persons without departing from the true spirit and scope of the invention as outlined in the appended claims. Hence, the interpretation of said claims should not be based on the present specific disclosure but rather on the pertinent prior art.

Having thus described my invention, what I claim as new and desire to secure by Letters Patent, is:

1. A box comprising a bottom of foldable material, a pair of upstanding side walls integral with said bottom, a cover substantially co-extensive with said bottom and integral with one of said walls, and a pair of upstanding end walls, each of said end walls consisting of three substantially co-extensive and overlapping flaps integral with said bottom and said two side walls, respectively, the height of the outermost flap of

each end wall being greater than that of the other flaps thereof, the difference in height between the flaps being substantially equal to the thickness of said cover.

5 2. A blank for making a box, comprising a substantially rectangular bottom portion, a pair of substantially identical side portions foldably hinged to opposite edges of said bottom portion, a pair of substantially identical end portions foldably hinged to the remaining edges of said bottom portion, the breadth of said side and end portions being substantially the same, a first pair of flaps foldably hinged to the free opposite edges of one of said side portions, a cover portion substantially identical with said bottom portion, said cover portion being foldably hinged to the remaining edge of said one side portion, and a second pair of flaps foldably hinged to the free opposite edges of the other of said side portions, said flaps and said end portions being substantially identical with one another, the breadth of said first pair of flaps exceeding the breadth of said second pair of flaps and of said end portions by substantially the same thickness of said blank.

20 HERMAN L. GREVE.
